UNITED STATES PATENT OFFICE.

ALFRED WEILAND, OF PHILADELPHIA, PENNSYLVANIA.

CARBURETER.

No. 911,349.

Specification of Letters Patent.

Patented Feb. 2, 1909.

Application filed April 28, 1908. Serial No. 428,792.

To all whom it may concern:

Be it known that I, ALFRED WEILAND, a citizen of the United States, residing in the city and county of Philadelphia, State of Pennsylvania, have invented a new and useful Carbureter, of which the following is a specification.

The object of my invention is to supply a gas engine with the proper mixture of gas and air under all conditions, and especially that type of engine used in automobiles and the like, where the demands for speed and power are constantly varying and the carbureter is subject to an ever shifting change of level.

It consists of a carbureter having a partition therein, forming a fluid reservoir and a mixing chamber and also providing a small auxiliary reservoir, the latter being so located and positioned as to be but slightly affected by any change in the level to which the carbureter may be subjected.

It further consists of an auxiliary air passage communicating with the auxiliary fluid reservoir at a point below the surface of the fluid therein, by means of which a quicker vaporization of the fluid in this reservoir takes place, resulting in the discharge of a much richer mixture to the main mixing chamber.

It further consists of an air throttle control adjustably mounted within the carbureter chamber, by means of which a definite proportion of air may be admitted, and which at the same time may move automatically to its maximum opening through the sudden opening of the throttle.

It further consists of other novel features of construction, all as will be hereinafter fully set forth.

Figure 1 represents a sectional elevation of a carbureter embodying my invention. Fig. 2 represents a section on line x—x, Fig. 1. Fig. 3 represents a section on line y—y, Fig. 1.

For the purpose of illustrating my invention, I have shown in the accompanying drawings those embodiments which will give reliable and satisfactory results in practice, although it is to be understood that the various instrumentalities of which my invention consists can be variously arranged and organized and that my invention is not limited to the precise arrangement and organization of these instrumentalities as herein shown.

Similar numerals of reference indicate corresponding parts in the figures.

Referring to the drawings:—1 designates a casing provided with air inlets 2, a fluid inlet 3 and a mixture outlet 4. In the present instance the fluid inlet 3 is formed in an extension 5 of an annulus 6, which latter, together with a closure 7, forms a partition dividing the casing 1 into a mixing chamber, and a fluid chamber 8. Within this chamber 8 is a float 9 preferably of cork or material of like qualities, to which is secured a valve stem 10 having a valve 11 thereon adapted to seat and close the fluid inlet opening 3, the end of said stem being provided with a guide 12 operating in an outlet 13 leading from the chamber 8 to an auxiliary reservoir 14, formed in the partition by means of an extension 15 secured to the closure 7. This extension 15 is exteriorly threaded in order to receive a cap 16 which is adapted to adjustably coöperate with the closure 7 to form an outlet passage 17 communicating with the auxiliary chamber 14 by means of suitably spaced apertures 18 in the wall of the extension 15. In the preferred form the side walls of the passage 17 are tapered from the apertures 18 in order to form a comparatively small exit opening 19 for the discharge of the fluid vapor. In order to maintain the cap 16 in adjusted position, a bushing 20 is provided, screwed upon the extension 15 to perform the functions of a lock nut. This bushing 20 is provided with an apertured flanged portion 21 adapted to receive a spindle 22, for a purpose to be hereinafter described. The air inlets 2 communicate with a mixing chamber 23 through a passage way formed between the annular flange partition 6 and an annulus 24 secured to a spider member 25 adapted for adjustment relative to the partition 6 so that the quantity of air which passes through the conduit may be accurately regulated. This spider 25 has formed integral therewith, a tubular extension 26, 100 suitably guided in a sleeve 27, the latter having an annulus 28 connected thereto by means of radial arms 28^x.

29 designates ribs secured to the annulus 28 and connecting the same to an annular ring 30, forming a slide valve for controlling the mixture outlet 4, or as more commonly known, the throttle. This throttle valve is

controlled in any suitable manner, in the present instance being operated through a series of cranks 31 and 32 and a link 33, the latter being connected with a reinforced portion 34 of the ring 30. The tube 26 is adapted for adjustment in order to vary the air inlet passage and in the present instance is accomplished by providing a threaded portion 35 on which an adjusting nut 36 is located, the same being controlled by a locking nut 37. It will be clear that the adjusting nut 36 rests upon the top of the sleeve 27 so that the position of the spider 25 and its wall 24 is accurately positioned relative to the annular partition 6, thereby controlling the quantity of air admitted to the mixing chamber 23. Upon the operation of the throttle lever 31 so as to open the throttle valve 30, the annulus 28 is raised and therefore carries with it the spider 25 so that as soon as any mixture is drawn off through the open throttle valve, the supply of air to the mixing chamber 23 will immediately be increased.

It will be noted that any undue pressure upon the lower side of the spider 25 will also act to raise the same, since there is no direct connection between the sleeve 27 and extension 26, the one merely resting upon the other through the medium of the adjusting nut 36. Such an action would take place if the throttle was opened very suddenly, since the increased suction would raise the spider 25 quickly in order to supply the correct ratio of air and gas to the motor. Within the tubular extension 26 is located the tube 22 having a passage 38 therethrough, the same leading from the exterior of the casing 1 to the interior of the auxiliary chamber 14 and communicates therewith through openings 39 formed in the end of the tube 22 and below the level of the fluid in the auxiliary reservoir. The end of this tube 22 is preferably formed as a conical valve 40 seating on the opening 13, whereby the regulation of the fluid to the auxiliary chamber 14 may be controlled. In view of the threaded engagement of this tube 22 with the annulus 21, a slight turn one way or the other will immediately result in a different adjustment of the valve 40 relative to its valve seat. In order to lock this member in its adjusted position, I preferably form on the end thereof, a knurled member 41 adapted to be engaged by a lock strip 42 suitably mounted on the top 43 of the casing 1. The auxiliary chamber 14 is a very essential feature of my invention in view of the fact that it is substantially at the center of the carburetor and is therefore less effected by any differences of level to which the carburetor may be subjected, and there will always be a small amount of fluid therein to maintain the correct ratio between the gas and air, and thus approximately keep the mixture properly proportioned to the speed. The

fluid enters the carburetor through a passage 44, communicating with the interior of the extension 5, from which latter the inlet 3 leads to the reservoir 8, control being had by means of the valve 11.

The operation of the device is as follows:— A supply of fluid enters through the channel 44 and as the float 9 at this time is in its lowest position, the valve 11 will be open and the fluid has an unrestricted flow upward through the inlet 3 into the chamber 8, in which it ascends and gradually raises the float until the desired height has been reached, when the float will of course shut off the valve 11 and prevent further entrance of the fluid. This, however, does not occur until a small amount of fluid has passed through the aperture 13 into the auxiliary reservoir 14 in which it is allowed to rise until the air inlets 39 in the tube 22 are covered. As soon as the throttle 30 is moved to open the mixture outlet 4, an upward suction will take place through the carburetor, through the agency of the engine's piston and a quantity of air will be drawn through the inlet 2. This inrush of air passes through the restricted passage way between the walls 6 and 24 and by the opening 19, from which a small quantity of the fluid is drawn off and intermixed therewith and the mixture then passes upwardly to the throttle valve to the engine. A further suction also takes place through the passage way 38 and a quantity of air passes down therethrough and emerges through the apertures 39, beneath the liquid in the auxiliary chamber 14, where it becomes much more intimately mixed with the fluid, producing a quicker vaporization and a very rich mixture which is drawn off through the opening 18 by the air rushing by. It will thus be clear that under the most exacting conditions there will be no flooding of the carburetor, since the annular sprayer is located some distance above the central needle valve. Furthermore attention is directed to the adjustable air throttle controlled by the lock nuts 36 and 37, and so mounted as to be lifted by the suction of the piston automatically to regulate the amount of air in case of a sudden opening of the throttle.

The action of my carburetor is to supply a mixture of gas and air to the engine which is accurately proportioned at all times to meet every speed demand upon the engine. This definite mixture I obtain from my automatic regulation, in connection with the auxiliary fluid reservoir in which at the maximum speed there is practically no liquid present, due to the fact that the entering air rushes past the opening 19 so rapidly and in such large quantities as to completely vaporize all of the liquid in this reservoir. However, on a sudden drop in speed, due to a load coming upon an engine, the air will consequently be somewhat diminished and the auxiliary reser-

voir gradually filled to its normal level with fuel, at which level the openings 39 from the central air supply tube are completely covered and therefore the admission of this air 5 will be through the liquid fuel, the air of course bubbling up through the liquid to produce a mixture sufficiently rich to meet this sudden demand upon the engine.

Having thus described my invention, what 10 I claim as new and desire to secure by Letters Patent, is:—

1. In a device of the character described, a casing, a partition in said casing forming a reservoir and a mixing chamber, an auxiliary 15 reservoir formed in said partition and communicating with said mixing chamber, an air inlet to said mixing chamber, a fluid inlet to each reservoir, means to control said fluid inlets, and means communicating with said 20 auxiliary reservoir whereby air is admitted thereto below the level of the fluid therein.

2. In a device of the character described, a casing, a partition in said casing forming a mixing chamber and a reservoir, an auxiliary 25 reservoir formed in said partition, a fluid inlet to said auxiliary reservoir, an outlet therefrom adjacent the air inlet to said mixing chamber, and means communicating with said auxiliary reservoir, whereby air is admitted thereto below the level of the fluid therein.

3. In a device of the character described, a casing, a partition therein forming a reservoir and a mixing chamber, an auxiliary reservoir 35 formed in said partition, an outlet therefrom having tapered sides, means to adjust one of said sides to vary the opening, an air inlet leading to said mixing chamber, and a mixture outlet from said mixing chamber.

4. In a device of the character described, a casing, a partition in said casing forming a reservoir and a mixing chamber, an auxiliary reservoir in said partition and communicating with said mixing chamber, a tube central 45 of said casing and communicating with said auxiliary reservoir, air outlets in said tube below the level of the fluid in said auxiliary reservoir, air inlets to said mixing chamber, a mixture outlet from said casing, a throttle 50 valve controlling said mixture outlet, and means coöperating therewith to vary the air supply to said mixing chamber.

5. In a device of the character described, a casing, a partition therein forming a reservoir and a mixing chamber, an auxiliary reservoir in said partition, a fluid inlet therefor, a valve for said inlet having a hollow stem, air outlets adjacent said valve, and means to adjust said valve to vary the admission of fluid 60 to the auxiliary reservoir.

6. In a device of the character described, a casing, a partition therein forming a reservoir and a mixing chamber, an auxiliary reservoir centrally located in said partition, a

fluid inlet therefor, a valve for said inlet, a 65 hollow stem on said valve, outlets adjacent said valve and below the surface of the fluid in said auxiliary reservoir whereby air is admitted, and means to adjust said valve to vary the admission of fluid. 70

7. In a device of the character described, a casing, a main reservoir, a mixing chamber formed therein, an auxiliary reservoir communicating with said main reservoir and said mixing chamber, an air inlet to said auxiliary 75 reservoir, and means to vary the admission of fluid to said auxiliary reservoir.

8. In a device of the character described, a casing, a main reservoir and a mixing chamber formed therein, an air inlet to said mixing chamber, an auxiliary reservoir communicating with said main reservoir and a mixing chamber, a mixture outlet, and means to control the admission of air to said mixing chamber according to the pressure in 80 said outlet.

9. In a device of the character described, a casing, a main reservoir and a mixing chamber formed therein, an air inlet to said mixing chamber, an auxiliary reservoir communicating with said main reservoir and said mixing chamber, a mixture outlet, and automatic means to control the admission of air to said mixing chamber according to the pressure in 85 said outlet. 90

10. In a device of the character described, a casing, a main reservoir and a mixing chamber formed therein, an auxiliary reservoir communicating with said main reservoir and said mixing chamber, means centrally located 100 of said auxiliary reservoir to control the admission of fluid thereto, an air inlet to said auxiliary reservoir, a mixture outlet, and a throttle valve controlling said outlet.

11. In a device of the character described, a casing, a partition therein forming a reservoir and a mixing chamber, an auxiliary reservoir in said partition communicating with said main reservoir and mixing chamber, an air inlet to said mixing chamber, an outlet from 110 said mixing chamber, means to control the admission of fluid to said auxiliary reservoir, and pressure actuated means to vary the admission of air to said mixing chamber.

12. In a device of the character described, 115 a casing, a partition therein forming a reservoir and a mixing chamber, an auxiliary reservoir in said partition communicating with said main reservoir and mixing chamber, a valve controlling the admission of fluid to 120 said auxiliary reservoir, an air inlet adjacent said valve, an air inlet to said mixing chamber, automatic means to control the admission of air thereto, and a mixture outlet.

ALFRED WEILAND.
